UNITED STATES PATENT OFFICE.

GEORGE SYLVESTER GRIMSTON, OF BROCKLEY ROAD, BROCKLEY, COUNTY OF KENT, ENGLAND.

GAS-BURNER APPARATUS.

SPECIFICATION forming part of Letters Patent No. 274,592, dated March 27, 1883.

Application filed September 25, 1882. (No model.) Patented in England February 24, 1882, No. 900.

To all whom it may concern:

Be it known that I, GEORGE SYLVESTER GRIMSTON, a subject of the Queen of Great Britain, residing at Brockley Road, Brockley, in the county of Kent, England, have invented 5 certain new and useful Improvements in Gas-Burner Apparatus, (for which I have received Letters Patent in Great Britain No. 900, dated 24th February, 1882,) of which the following 10 is a specification.

This invention has for its object improvements in gas-burner apparatus.

In gas-burner apparatus constructed according to this invention the flame is entirely inclosed, and all air passing to it to support combustion has to pass through a regenerator kept heated by the products of combustion as they pass away. The flame also may be directed downward, and then allowed to curl upward 15 under the edge of a deflector, so that the flame may be at the bottom of the lamp, and consequently avoid any downward shadow. To effect this the gas is supplied by a vertical supply-pipe to a metallic chamber, from the bottom of which descend a number of tubular jets, preferably ranged in a circle at a short 20 distance apart one from the other. Descending from the bottom of the gas-chamber is also a metallic cylinder, which surrounds and is of 25 larger diameter than the circle of gas-jets. The metallic cylinder is open at bottom and descends somewhat lower than the ends of the tubular gas-jets. The lower end of the cylinder is surrounded by a glass basin, preferably 30 so shaped that every part of it is, as near as 35 may be, equidistant from the nearest point of the cylinder. The top of the glass vessel is secured to the lower end of an outer metallic cylinder, which surrounds the upper part of the 40 cylinder before mentioned. Air tubes or passages are provided, leading from the outer cylinder to the inner one, to admit air to the interior of the inner cylinder to support the combustion of gas issuing from the burner. Between 45 the air-inlet passages are spaces for the products of combustion to pass between on their way to a chimney. This chimney rises up from the top of the outer cylinder. The jets of gas issuing from the burner are projected 50 downward, and when the burners have been lighted long enough to produce an upward

draft in the chimney they curl upward around the lower end of the inner cylinder, between it and the outer glass, and the products of combustion, rising upward to the chimney, 55 pass between the air-inlet tubes or passages, so that all the air passing to the burners gets highly heated, and as the flame is entirely inclosed the heating of the incoming air is carried to a very high degree. Preferably the 60 air-passages leading to the interior of the inner cylinder are formed of numerous circular tubes radiating from it to the outer cylinder, which carries the glass; but they might be otherwise formed to effect the same object. 65 If desired, the outer cylinder, which carries the glass, might be itself surrounded by another glass cylinder of larger diameter, and this glass cylinder might extend downward so as to surround the glass which incloses the burner. 70 In this way the outer ends of the air-passages would be protected from currents of air blowing directly into them. The outer cylinder, of glass, might also be closed at the top, so that all air passing to the burner would then have 75 to ascend between the inner and outer glasses. In this way the heating of the air passing to the burner would be still further increased. In place of the burner being set so that the flame is directed vertically downward, it might be 80 set so as to direct the flame horizontally.

In order that my invention may be fully understood and readily carried into effect, I have shown in the drawings hereto annexed a gas-burner apparatus constructed in the manner I prefer.

Figure 1 is a vertical section of the apparatus, and Fig. 2 a horizontal section on the line 1 1 in Fig. 1.

A' is the gas-supply pipe, terminating at its 90 lower end in a gas-chamber, A, from which descend a number of small tubes, B, ranged in a circle, as shown at Fig. 2. C is the cylinder, of copper, attached at its upper end to the exterior of the gas-chamber A. The bottom 95 end of the cylinder is open, and is somewhat below the bottom of the tubes B D.

D are copper tubes radiating out from the upper part of the cylinder C. Their outer ends pass through and are secured in a copper cylinder, E.

F is a chimney which rises up from the top

of the cylinder E. This chimney may be of thin sheet metal.

G is a cylinder, of thin sheet-copper, surrounding the cylinder E. It is closed over inward at the top and secured to the top of the cylinder E by rivets or otherwise. This cylinder protects the ends of the tubes D from currents of air being blown directly into them.

A bell-shaped glass shade, H, may be carried from the top of the cylinder G, as shown, by three or more hinged pieces, I, which can be turned up into the position shown by dotted lines to admit of the shade H being put in place or removed.

J is the glass bowl by which the lower end of the cylinder E is closed. It has an outward flange around its upper edge, which rests on an asbestos ring, K. The asbestos ring is carried by a flange, L, which projects inward from a metallic ring, M. This ring just fits within the lower end of the cylinder E and can be locked to it in any suitable manner. In the drawings the cylinder E is, for this purpose, shown to have two or more pins, E', projecting inward from it, and the ring M has a corresponding number of L-shaped slots cut into it from its top edge. When the ring M is pushed upward into the cylinder E the pins E' are made to enter the vertical parts of the slots. A partial turn is then given to the ring, so that the pins shall enter the horizontal portions of the slots, and so hold the ring up.

N N are knobs or handles by which the ring M can be turned.

O is a guard composed of an open net-work of fine wire to serve as a guard to the glass basin J and keep it from being accidentally broken. The bottom of the glass bowl is, as shown, formed with an inward central conical projection, so that approximately the bottom of the glass bowl J shall at all parts be at equal distances from the nearest point of the cylinder C. By this conical projection the stream of heated air and gas issuing from the bottom of the cylinder C, and urged forward by the draft of the chimney, is deflected uniformly outward to form an outwardly-spreading flame, which is confined in the comparative narrow channel between the cylinder C and the bowl J. The sides of the bowl conduct the heated products of combustion upward and cause them to pass between the several tubes D, so that the products of combustion may give off their heat to the incoming gas and air.

Having thus described the nature of my invention and the manner of performing the same, I would have it understood that I claim—

1. The combination of the cylinder C, downward through which air is caused to pass, the jets delivering gas within the cylinder at its lower end, and means against which the flame impinges, and by which it is deflected outward and upward in annular form around the lower end of the cylinder as it issues downwardly therefrom, substantially as and for the purpose hereinbefore set forth.

2. The combination of the cylinder C, from the lower end of which the flame issues, means for supplying air to the cylinder above said end, means for supplying gas in jets to and within the cylinder at the lower end, means against which the downwardly-issuing flame impinges, and by which it is deflected outward and upward, and means for confining and conducting the flame and products of combustion along the outside of the cylinder in passing off, substantially as and for the purpose hereinbefore set forth.

3. The combination of the cylinder C, from the lower end of which the flame issues, the radiating-tubes supplying air to the upper part of the cylinder, means for supplying gas in jets to the cylinder, means for deflecting the flame outward and upward, and means for conducting the flame and products of combustion along the outside of the cylinder and in contact with the air-supply tubes in passing off, substantially as and for the purpose hereinbefore set forth.

4. The combination, with gas-burning apparatus in which gas is caused to issue downward to form an annular flame, of a bowl, J, with a central conical projection confining the flame within a channel, substantially as described.

5. The combination of the cylinder from one end of which the flame issues, means for conducting gas to the opposite end of said cylinder, the gas-jet tubes discharging within the cylinder and near that end from which the flame issues, the flame-deflecting bowl, the cylinder E, and the air-supply tubes, substantially as and for the purpose set forth.

6. The combination of the cylinder C, its air-supply tubes, the gas-chamber, the tubes B, the bowl J, the cylinder E, the gas-supply pipe, and the chimney, substantially as and for the purpose set forth.

GEORGE SYLVESTER GRIMSTON.
